UNITED STATES PATENT OFFICE.

GEORGE F. SEITZ, OF PHILADELPHIA, PENNSYLVANIA.

PRINTER'S FURNITURE.

1,149,957.

Specification of Letters Patent. Patented Aug. 10, 1915.

Application filed May 6, 1914. Serial No. 836,796.

To all whom it may concern:

Be it known that I, GEORGE F. SEITZ, a citizen of the United States, residing at Philadelphia, in the county of Philadelphia and State of Pennsylvania, have invented 5 certain new and useful Improvements in Printers' Furniture, of which the following is a specification.

My invention relates to furniture for the 10 use of printers, particularly to spacing members, and has for its object the provision of various spacers so constructed as to facilitate their separation for the insertion of type, brass rule, or other spacers, and also 15 provided with means whereby a superfluous spacer may be readily removed without prying apart or otherwise disturbing the remaining spacers or the type in a line, chase or form.

20 Other objects and advantages such as simplicity, efficiency, cheapness and the general improvement of the art will be brought out in the following description and illustrated in the accompanying drawings, in 25 which:

Figure 1 is a perspective view of the ends of lines of composition comprising my improved spacing members, Fig. 2 is a perspective view of my spacers adapted for use 30 between individual type, Fig. 3 is a perspective view of one of my spacers adapted for use between successive lines of composition, Fig. 4 is a perspective view of one of my spacing members in a larger size and of the 35 form called furniture, and Fig. 5 is a cross sectional view thereof.

Referring more particularly to the drawings, the numeral 1 designates one of my spacing blocks, as a whole, adapted for use 40 as a spacer between individual type or for filling out lines of type. The spacer may be of any point or size as em quads, en quads, 4 and 5 ems, spacer, etc., and may be of any length as desired, the construction being entirely unaffected by the size. At a point 45 adjacent its upper end the spacer 1 is provided with beveled shoulders 2 on its opposite edges parallel with the usual indicating grooves formed in the spacer. An extension 50 or rib 3 is formed on the upper end of the spacer and has its sides 4 flush with the sides of the body of the spacer, and its front 5 and back 6 spaced inwardly of the front and back of the body, the front and back extending upwardly from the top line of the bevel.

From the foregoing it will be apparent that when a plurality of my spacers are arranged in a line, the beveled shoulders 2 will permit of the ready insertion of a brass 60 rule or the moving of the entire line for the insertion of a spacing slug or a piece of furniture.

In order that the spacers may be separated easily to facilitate the insertion of a 65 type or another spacer between them, I preferably bevel the upper edges of the sides 4 of the extensions or ribs 3, as shown at 7, so that they may be engaged by the tongue of a composing rule, a knife blade 70 or the like for readily and easily separating them.

The extensions or ribs 3 being parallel with the grooves or guide notches formed in spacers perform another useful function by 75 indicating whether or not the spacer is inserted in the correct position. This feature is valuable as some quads are so nearly square that the difference is not readily noticeable but when set in the wrong position will not lock up correctly in the form 80 as is well understood.

It is to be noted that the extensions or ribs 3 may be easily engaged by tweezers for removing the spacer, thereby eliminating 85 the difficulty experienced in removing the common form of spacer or quad in which prying apart is necessary to allow the tweezers to engage the sides of the spacer 90 to be extracted.

Referring more particularly to Fig. 3 of the drawings it will be seen that I have provided a slug or lead for use between consecutive lines of type which is constructed on the principle of my spacer or quad. The 95 slug or lead 8 is beveled along its upper longitudinal edges as shown at 9 and is further provided with an extension or rib 10 to be engaged by tweezers or the fingers for removing it.

Figs. 4 and 5 show my invention applied to what is commonly called furniture or labor saving furniture. In this adaptation the blocks 11 are provided upon their upper faces with extensions or ribs 12 adapted to 105 be engaged by tweezers or fingers for lifting the blocks from a form. These extensions or ribs also prevent the blocks from being set in the form in any position other than the correct one as will be obvious. Furthermore by forming the blocks with recesses 13 in their bottom sides they may be stacked 110

one upon another as the extension or rib 12 on one block would then be disposed in the recess 13 in the next block above it. The edges of the blocks 11 are also beveled as at 5 14 to permit the ready insertion of a brass rule or thin leads between them or to allow them to be easily separated for the insertion of slugs or other blocks or strips of furniture.

10 By the foregoing it will be apparent that the extensions or ribs formed on the upper surfaces of my spacers permit of their ready removal by tweezers, and that when a plurality of my spacers are arranged in a number 15 of lines the beveled shoulders designated by 2, 9 and 14 permit of the ready insertion of brass rules horizontally, and that the beveled shoulders designated by 7 and 14 permit of the ready insertion of brass 20 rules crosswise, and that these beveled shoulders facilitate the moving of an entire line or lines horizontally or crosswise for the insertion of spacing slugs or pieces of furniture as may be required.

25 Having thus described my invention what I claim is:

1. A spacing block having its longitudinal edges beveled, and a projection formed on its upper face and having two of its faces 30 flush with the unbeveled edges of said block,

and its other two faces terminating within the beginning of said bevels, the transverse edges of said projection being beveled.

2. A spacing block having its upper longitudinal edges beveled, and a projection 35 on its upper surface between said bevels, said projection having its transverse edges beveled.

3. A spacing block having a groove 40 formed on one of its sides and its upper longitudinal edges beveled, and a longitudinal projection rectangular in cross section on its upper face between said bevels, and having its transverse upper edges beveled. 45

4. A spacing block having a flat upper surface, a rib rectangular in cross section centrally and longitudinally disposed on said upper surface and extending the full length of said upper surface, the longitudinal edges of the top surface of said rib terminating within the side edges of the top surface of said block and at an appreciable distance therefrom, said rib having its transverse edges beveled. 50

55 In testimony whereof I hereto affix my signature in the presence of two witnesses.

GEORGE F. SEITZ.
